US00D872502S

(12) **United States Design Patent** (10) **Patent No.:** **US D872,502 S**
(45) **Date of Patent:** **** Jan. 14, 2020**

(54) **NECK PILLOW**

(71) Applicant: **Jun Xu**, Zhejiang (CN)

(72) Inventor: **Jun Xu**, Zhejiang (CN)

(73) Assignee: **Lanxi Yide Textile Co., Ltd**, Lanxi, Zhejiang (CN)

(**) Term: **15 Years**

(21) Appl. No.: **29/656,671**

(22) Filed: **Jul. 16, 2018**

(30) **Foreign Application Priority Data**

Jan. 18, 2018 (CN) 2018 3 0023178

(51) **LOC (12) Cl.** **06-09**

(52) **U.S. Cl.**

USPC **D6/601**

(58) **Field of Classification Search**

Primary Examiner — Michelle E. Wilson
Assistant Examiner — Sanjeev Paul

(57) **CLAIM**

The ornamental design for a neck pillow, as shown and described.

DESCRIPTION

FIG. 1 is a perspective view of a neck pillow showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
